CLAIM

The ornamental design for a door for drum washing machine, as shown and described.

DESCRIPTION

FIG. 1 is a perspective view of a door for drum washing machine, showing my new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is another perspective view thereof in an environment of use.

The broken lines in the figures illustrating portions of the door for drum washing machine and environmental structure form no part of the claimed design.

1 Claim, 7 Drawing Sheets
